UNITED STATES PATENT OFFICE

2,550,184

LOCK HAVING KEY EJECTING MECHANISM

R L Brown, Corsicana, Tex., assignor of one-half
to J. N. Garitty, Corsicana, Tex.

Application January 3, 1950, Serial No. 136,506

2 Claims. (Cl. 70—388)

1

The present invention relates to new and useful improvements in keys of the cylinder type whereby the key will automatically be ejected from the lock after the key has been turned to return the lock to its locked position.

An important object of the invention is to provide a lock of this character whereby the key will be ejected from the lock and is designed primarily for use with ignition keys and locks for automobiles to avoid the danger of the theft of the car by leaving the key in the lock.

A further object of this invention is to provide an ignition key and lock embodying an ejecting rod at the back edge of the key which compresses a spring mounted in the lock barrel to eject the key therefrom should the key accidentally be left in the lock.

A still further object is to provide a key ejecting mechanism in which the spring ejecting means is enclosed in the lock barrel to avoid injury thereto by frequent handling of the key.

A still further object is to provide a device of this character simple and practical in construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a longitudinal sectional view of the lock showing the key in position therein.

Figure 2 is a front elevational view; and

Figure 3 is a perspective view of the key.

Referring now to the drawing in detail the type of lock herein illustrated embodies a fixed cylindrical body 10 and a rotatable barrel 11 therein formed with a keyway 12 and wherein the body and barrel are provided with a series of relatively arranged spring pressed plungers 13 which normally lock the barrel to the body, but which are moved into unlocking relation by the action against the free end of the plungers by the tumbler engaging front edge of a key 14 when the key is forcibly inserted in the keyway.

The back edge of the key 14 is formed with a rod or pin 15 positioned in spaced parallel relation to the back edge of the key and is received in a bore 16 of the barrel 11 for compressing a coil spring 17 against a screw 18 threaded in the rear end of the bore. A washer 19 is suitably secured to the front end of the spring to prevent mutilation of the spring by the compressing action of the rod or pin 15.

2

In the operation of the device as the key 14 is inserted in the barrel 11 the rod or pin 15 is also inserted in the bore 16 of the barrel to compress the spring 17. When the key is turned to its "on" position the key is retained in the lock barrel in the usual manner and when the key is turned to its "off" position the key is free to slide in and out of the keyway 12 and should the key accidentally be left in the lock the spring 17 will then eject the key so that the key will not remain in the lock.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A cylinder-type lock having a rotatable plug, said plug having a key shank passage and a bore parallel to the key shank passage, and a coil spring in the bore for ejecting a key having a shank and a pin parallel to said shank when inserted in the key shank passage and bore respectively.

2. A cylinder-type lock having a rotatable plug, said plug having a key shank passage and a bore parallel to the key shank passage, yieldable means in the bore for ejecting a key having a shank and a pin parallel to said shank when inserted in the key shank passage and bore respectively.

R L BROWN.
